SPACE DISCHARGE DEVICE HAVING GRID
OF VARYING ELECTRON TRANSPARENCYAngelo Montani, Woodhaven, N. Y., assignor to
Automatic Electric Laboratories, Inc., Chicago,
Ill., a corporation of Delaware

Application November 28, 1947, Serial No. 788,490

3 Claims. (Cl. 250—27)

1

The present invention relates in general to circuit arrangements utilizing space discharge devices of the electron beam type.

It is an object of the present invention to provide a circuit including a space discharge device of the electron beam type in which the normal parameters, such as the Mu and Gm etc., of the tube may be varied at the will of the operator.

Another object of the invention is the provision of a circuit including a space discharge device of the electron beam type so arranged as to perform the functions of an FM discriminator and limiter combined.

Other objects and features of the invention will become apparent upon a further perusal of the specification.

Briefly these objects are accomplished by providing a special control grid and a collecting plate in a tube structure similar to a conventional cathode ray tube. The control grid is so constructed as to have a variable electron transparency, the grid mesh being the least dense in the middle of the grid in the region through which the undeviated electron beam will pass, and gradually becoming more dense on either side of the middle region and finally becoming opaque at each end of the grid. The position of the beam of electrons on the grid is determined by means of a suitable voltage applied to a pair of deflecting plates. The electron transparency of the grid region through which the electron beam is caused to pass obviously determines the characteristics of the tube. It is apparent then that the tube characteristics may be varied by causing the electron beam to pass through different grid regions under control of the voltage applied to the deflecting plates.

When used as an FM discriminator the deflecting plates are connected to the last IF stage of the receiver. The electron beam will now be caused to oscillate back and forth across the grid, the angle through which the beam swings will be proportional to the frequency deviation of the FM signal. If the electron beam swings through a small arc, that is confined mostly to the middle region of the grid where the mesh is the least dense, the average plate current will be the greatest. As the arc through which the electron beam swings increases, the beam encounters the more dense regions of the grid and the average plate current consequently decreases until a minimum average plate current is reached when the arc through which the beam swings is so great as to cause the beam to swing over the

opaque regions at either end of the grid. Thus the tube produces an average plate current which is a function of the frequency deviation which of course is the function and purpose of an FM discriminator.

The invention will be better understood from the following description when taken in conjunction with the drawings in which:

Fig. 1 discloses one form of the invention in 10 a circuit for use as a combined FM discriminator and limiter.

Fig. 2 shows a set of analytical curves for use 15 in explaining the operation of the device.

Fig. 3 shows an alternative method of energizing the deflecting plates by a direct current source to thereby lock the beam in any desired position.

Referring to Fig. 1 of the drawing, there is 20 shown a cathode ray tube having the conventional heater 1, cathode 2, and beam forming electrodes 3, 4, and 5 all of which are energized by a suitable battery 15 or the like. The pencil like electron beam, indicated by the broken line 7, passes between a pair of electrostatic deflecting electrodes 6 which are positioned on opposite sides of the beam axis. It is to be understood that the equivalent magnetic deflecting coils or other suitable means may be substituted for the electrostatic deflecting electrodes, if desired. The electron beam 7 is caused to scan a 25 rectilinear path along varying portions of control grid 8. Grid 8 is constructed so as to have a varying mesh density along its length as is shown. The solid portions 17 at either end of 30 grid 8 are opaque to the electron beam and actually become collecting plates. Grid 8 is energized through resistance 12 by a suitable battery 13 or the like. Electrode 9 is a collecting plate and is energized by battery 15 through resistance 11 across which the audio output voltage 35 is developed. The output voltage developed across resistance 11 may be resistance coupled or capacitance coupled, as is shown, to the next stage of audio equipment.

40 The deflecting plates 6 are connected to the output from the last IF stage of the receiver, the beam of electrons thus being deviated from its normal path in accordance with the voltage developed by this stage. The IF transformer 16 45 is not tuned to the center, or unmodulated, carrier beat frequency as is normally the case but is rather tuned to the lowest beat frequency occurring when the FM carrier is 100% modulated. Actually the IF transformer 16 may be tuned below this frequency or it may be tuned above

2

the highest beat frequency to which the IF signal will deviate when the carrier is 100% modulated and the device will function satisfactorily as a discriminator.

Consider now the operation of the device of Fig. 1 in conjunction with the analytical curves of Fig. 2. The curve on the right hand side of Fig. 2 shows the FM modulating signal which is causing the FM carrier frequency, indicated at *g*, to deviate between the points *f* and *h*, *f* being the lowest frequency and *h* being the highest. The IF transformer 16 is tuned to the beat frequency occurring when the carrier frequency is at *f*, it being assumed that the carrier is 100% modulated. At the point *a* on the modulating signal, the voltage induced on the deflecting plates 6 by the IF transformer 16 will be a median value and the electron beam will scan all of the sparsely meshed region of grid 8 and part of the denser regions. The average plate current for this condition will be some value such as *a'* in the left hand curve of Fig. 2. As the modulating voltage increases to point *b* causing the carrier frequency to increase to point *h*, the voltage developed across transformer 16 decreases because the beat frequency is deviating farther away from the resonant frequency of transformer 16. Under this condition the beam will not swing as far as at point *a* and will consequently scan just over the center region of grid 8 thus producing an increased average plate current such as is indicated at point *b'* in the left hand curve of Fig. 2. The analysis for the point *C* is the same as for point *a* resulting in the decrease of the average plate current to point *C'*. At point *d* the carrier frequency has decreased to the point *f* and the beat frequency will be at the resonant frequency of transformer 16 hence the voltage on the deflecting plates 6 will be a maximum. Under this condition the beam will make its maximum swing, scanning all of the meshed portions of grid 8 just up to the opaque portions 17. The beam thus scans the more dense regions of grid 8 resulting in a decrease in the average plate current to a point indicated at *d'*. The analysis for point *e* is again the same as for point *a* resulting in an increase of the average plate current to the point *e'*.

It is clear from the foregoing analysis that the average plate current flowing through resistance 11 varies in a manner conforming to the signal modulating the FM carrier. The variations in the electron transparency of grid 8 may be made to conform with the selectivity curve of the last IF stage or in fact may be made to conform with any desired law.

It will be noted that grid 8 is slightly positive by virtue of battery 13 thus a current will flow in the grid circuit developing a voltage across resistance 12. This voltage is filtered at 14 and connected to a preceding IF amplifier stage. The purpose of this arrangement is to cause the tube of Fig. 1 to act as a limiter as well as a discriminator. The filtered voltage emanating from filter 14, when the beam is scanning between the solid portion 17 of grid 8, will not vary appreciably but if a disturbing AM signal should become superimposed upon the FM signal the beam would scan over the solid portions 17, resulting in a large increase in the grid current and an increase in the filtered voltage. This voltage may be utilized in a preceding IF amplifier stage for momentarily reducing the gain in any well known manner. Thus any unwanted AM signal will be ineffective to cause distortion in the audio

output by reason of the feedback from the grid circuit of the tube in Fig. 1.

The tube of Fig. 1 may also be used as a triode. The deflecting voltage applied to plates 6 in this case might come from any suitable direct current source such as for example is shown in Fig. 3. In Fig. 3 the deflecting plates 6 are energized by means of the potentiometer 31 connected across battery 30. This arrangement enables the operator to position the beam through any desired region of grid 8 to thereby choose the operating characteristics of the tube. The grid circuit would then be connected in a suitable manner for which the tube as a triode is to be used.

The tube may also be used as a vacuum tube voltmeter, the voltage to be measured being applied to the deflecting plates and the plate current reading being calibrated to read voltage.

While what is now considered to be the preferred form of the invention has been illustrated, it is to be understood that numerous modifications may be incorporated therein without departing from the true spirit and scope of the invention as defined in the subjoined claims.

25 What is claimed is:

1. In a frequency modulation discriminator system, means for developing and projecting a beam of electrons in a given path, a grid located in said path for screening said projected beam, said grid having a mesh of varying electron transparency ranging from a region of relatively maximum transparency through a region of relatively minimum transparency to and including an opaque region, a circuit connected to said grid, means for impressing a potential upon said grid to cause a current flow in said circuit, means for filtering a potential from said current flow, means for causing said beam to scan said grid, control means responsive to received frequency signals for controlling said fourth mentioned means to cause said beam to variably scan only said transparent regions of said grid, the amount of said current flow varying only in relatively small values responsive to said variable scanning of said transparent regions, said filtered potential varying in corresponding small values responsive to said value variations in said current flow, said control means responsive to received frequency signals and a received interfering signal for controlling said fourth mentioned means to cause said beam to scan said opaque region of said grid, said current flow rising to a relatively high value responsive to said scanning of said opaque region, said filtered potential rising to corresponding high value responsive to said high value rise in said current flow.

2. In a frequency modulation discriminator system as claimed in claim 1 wherein said received frequency signals consist of received frequency-modulated intermediate frequency signals, and wherein said received interfering signal consists of a received stray amplitude-modulated signal superimposed on one of said received frequency-modulated intermediate frequency signals.

3. In a frequency modulation discriminator system, means for developing and projecting a beam of electrons in a given path, a collecting plate located in said path, an output circuit connected to said plate, a grid located in said path for screening said beam projected towards said plate, said grid having a mesh of varying electron transparency ranging from a region of relatively maximum transparency through a region of relatively minimum transparency to and including an opaque region, a grid circuit connected to said

grid, means for impressing a potential upon said grid to cause a current flow in said grid circuit, means for filtering a potential from said current flow and for extending said filtered potential to an intermediate frequency amplifier stage, means for causing said beam to scan said grid, control means responsive to received frequency signals for controlling said fourth mentioned means to cause said beam to variably scan only said transparent regions of said grid, electrons of said beam impinging upon said plate responsive to said variable scanning of said transparent regions to cause a current flow in said output circuit, the number of electrons impinging upon said plate varying as the amplitude of said variable scanning of said transparent regions increases and decreases, the amount of said current flow in said output circuit varying responsive to said variance in the number of said impinging electrons, the potential of said current flow in said output circuit correspondingly varying responsive to said variations in the amount of said current flow in said output circuit, the amount of said current flow in said grid circuit varying only in relatively small values responsive to said variable scanning of said transparent regions, said filtered potential varying in corresponding small values responsive to said value variations in said current flow in said grid circuit, said control means

responsive to received frequency signals and a received interfering signal for controlling said fourth mentioned means to cause said beam to scan said opaque region of said grid, said current flow in said grid circuit rising to a relatively high value responsive to said scanning of said opaque region, said filtered potential rising to corresponding high value responsive to said high value rise in said current flow in said grid circuit, said high value rise in said filtered potential causing a reduction in the gain of said amplifier stage to control the intensity of said beam in a sense to render said potential of said current flow in said output circuit independent of said scanning of said opaque region of said grid.
